UNITED STATES PATENT OFFICE

CHARLES A. DOMLER, OF PROVIDENCE, RHODE ISLAND, ASSIGNOR TO THE HADLEY COMPANY, INC., OF PROVIDENCE, RHODE ISLAND, A CORPORATION OF RHODE ISLAND

BRACELET ATTACHMENT

Application filed December 31, 1929. Serial No. 417,730.

This invention relates to bracelet attachments, and pertains more particularly to improvements in clasps for releasably holding together the folding members of an extensible connector for wrist watch bracelets. The principal object of the invention is to provide an attachment or connector of the aforesaid type which is simple and economical to manufacture, which may be quickly 10 and securely locked in closed position yet easily readily opened to extend the connector, which is attractive in appearance and which is composed of a small number of parts so constructed and arranged that the closed connector is unusually thin, and which has a relatively small portion exposed to view between the connected ends of the bracelet proper and presenting a smooth outer surface which may be embossed or decorated to simulate an integral part of the bracelet. Further objects reside in the improved structural features of the connector and its latch member, as hereinafter described and pointed out in the appended claims.

25 The recommended embodiment of the invention which is chosen for the purpose of illustration in the accompanying drawings is associated with a flexible link bracelet, but it will be understood that the precise construction of the connected bracelet sections is not essential to the present invention. In the drawings:

Fig. 1 is a top view of a portion of a bracelet equipped with improved attachment or 35 connector;

Fig. 2 is a side view thereof, showing the connector in closed position;

Figs. 3 and 4 are views similar to Fig. 2 showing respectively preferred modes of 40 opening and closing the connector;

Fig. 5 is an enlarged bottom view of the closed latch; and

Fig. 6 is an enlarged longitudinal section through the latch as shown in Fig. 2, with 45 certain parts in side elevation.

In the illustrated embodiment of the invention, the extensible connector and its latch constitutes a unitary attachment of the bifold type for connecting corresponding ends of a 50 pair of bracelet sections 7 and 8, the opposite

ends of the bracelet sections being fastened to a wrist watch when the bracelet is used for that purpose. The attachment accordingly comprises a pair of substantially rigid members, preferably thin, metal plates 9 and 10, pivoted together at one end by a hinge 11 to swing into juxtaposed, overlapping relation. The connector plates may be curved as shown, to conform to the shape of the wearer's wrist, and the lower plate 9 is preferably larger than the upper plate 10.

The forward or free end of the lower plate 9 is bent rearwardly to provide a loop 12 to which the bracelet section 7 may be attached, and the extremity of the plate is turned 65 downwardly toward the upper face of the plate to furnish a shoulder or hook 13 terminating short of said face. The forward end of the upper plate 10 is formed with a shoulder 14 providing an upwardly offset ledge 70 or platform 15 parallel to the main body of the plate; and its extremity is cut through longitudinally to provide a central tongue 16 which is rolled downwardly to embrace a transverse pivot pin 17, and a pair of side 75 tabs 18 which are turned downwardly and rearwardly toward the shoulder 14. A transverse tube 19 is fastened as by soldering to the outer face of the plate 10, preferably behind the shoulder 14, and serves as a convenient attachment for the end of the bracelet section 8.

The plates 9 and 10 are releasably held in overlapping or folded relation by a latch member which is pivoted to one of said plates, 85 preferably at the forward end of the upper plate 10, and is arranged to latch with the other plate in locking engagement, preferably under the hook or shoulder 13 at the extremity of plate 9. The latch preferably 90 comprises a hook 20 engageable beneath the shoulder 13, hinge sleeves 21 journaled on the pivot 17, and a releasing arm or lever 22 overlying the ledge 15, all of said portions being shaped from a single piece of sheet 95 metal by suitable forming operations. For example, the sleeves 21 may be formed by rolling downwardly a pair of ears cut from the sides of the metal piece and arranged to straddle the tongue 16 on the pivot 17 100

(Fig. 5), and the arm or lever 22 may be a flat central extension of said piece adapted to lie flatwise upon the outer face of the ledge 15 when the latch is engaged. The end of the arm 22 preferably carries a pair of studs 23 engaging in complementary apertures 24 in said ledge, frictionally to hold the latch in locking position.

The swinging arc of the latch member is preferably limited by providing slots 25 in the sleeves 21 and complementary tongues 26 struck from the tabs 18, the tongues 26 projecting into the slots 25, as best shown in Figs. 5 and 6, so that the ends of the tongues 15 abut the ends of the slots when the arm 22 has been swung upwardly to the desired extent, for example to the position shown in Fig. 3. In such position, the hook 20 has been disengaged from the shoulder 13 by 20 lifting the lever 22 with the finger nail, and the plate 10 may be swung upwardly of the plate 9, as indicated in broken lines in Fig. 3, to extend the effective length of the bracelet and permit it to be drawn over the hand.

The connector plates may, if desired, be locked in closed position (Fig. 2) by reversing the operations just described, that is by 25 folding the plate together and pressing the lever 22 downwardly to swing the hook 20 under shoulder 13, but it is recommended that the lever be snapped to closed position initially and that the plates be then swung together, as illustrated in Fig. 4, and pressed into locking position. By this simple and 30 effective operation the hook 20 rides over the shoulder 13, owing to the resiliency of the upper plate 10 which is arched slightly as indicated in Fig. 4, and then snaps under the shoulder as the plate straightens and 35 lengthens to normal position.

Although the flexible bracelet sections connected by the attachment above described may be made of any suitable material, such as metal links, or chains, leather or fabric 40 straps, or similar materials, the link bracelet shown in the drawings is particularly appropriate for association with the described connector. This bracelet comprises a series of parallel metal tubes or links 27 flexibly interconnected by U-shaped staples 28 having legs received within opposite ends of adjacent links and straddling the contiguous walls thereof. The ends of the corresponding legs of each complementary pair of staples are 45 detachably interconnected by complementary interengaging recesses and projections as shown at 29, Fig. 5, so that the staples may be inserted or removed as desired. With such a construction, the bracelet sections 7 and 8 50 may conveniently be attached to the folding connector by locking the outer legs of the end staples 28 within the loop 12 of plate 9 and the tube 19 of plate 10, respectively (Figs. 5 and 6). Hence, there is substantially no 55 interruption in the pleasing continuity of

the bracelet structure, except at the relatively short space occupied by the latch member; and the exposed surface of the latch may be marked with lines 30 (Fig. 1), simulating the appearance of the bracelet links and staples.

From the foregoing it is evident that the improved attachment furnishes a connector which is structurally compact and neat in appearance, which is comfortable in use and easy to operate either to lock or release the extensible connector plates, and which avoids the objectionable thickness and clumsy appearance of the attachments heretofore in use. It will be understood that the precise structural details of the elements herein described may be varied to suit particular purpose without departing from the spirit of this invention as defined in the following claims.

I claim:

1. An attachment for wrist watch bracelets or the like, comprising a pair of foldable connector plates pivoted together to swing into overlapping relation, connections on the respective plates remote from the pivot for securing bracelet ends to the attachment so that the bracelet is extended when the plates are unfolded, the forward end of one of the plates having a shoulder projecting toward the face of said plate, and a latch pivoted at the forward end of the other plate and having a hook detachably engaging said shoulder to lock the attachment in folded position.

2. An attachment for wrist watch bracelets or the like, comprising a pair of foldable connector plates pivoted together to swing into overlapping relation, connections on the respective plates remote from the pivot for securing bracelet ends to the attachment so that the bracelet is extended when the plates are unfolded, one of said plates being longer than the other and the free forward end of the longer plate being bent rearwardly and having a shoulder projecting toward the face of the plate, a latch pivoted at the free end of the shorter plate, the latch having a hook detachably engageable with said shoulder to lock the attachment in folded position.

3. An attachment for wrist watch bracelets or the like, comprising a pair of foldable connector plates pivoted together to swing into overlapping relation, connections on the respective plates remote from the pivot for securing bracelet ends to the attachment so that the bracelet is extended when the plates are unfolded, one of said plates being longer than the other and the free forward end of the longer plate being bent rearwardly and having a shoulder projecting toward the face of the plate, a latch pivoted at the free end of the shorter plate, the latch having a hook detachably engageable with said shoulder to lock the attachment in folded position, and

means for limiting the swinging movement of the pivoted latch.

4. An attachment for wrist watch bracelets or the like, comprising a pair of foldable connector plates pivoted together to swing into overlapping relation, connections on the respective plates remote from the pivot for securing bracelet ends to the attachment so that the bracelet is extended when the plates are unfolded, one of said plates being longer than the other and the free forward end of the longer plate being bent rearwardly and having a shoulder projecting toward the face of the plate, and a latch pivoted at the free end of the shorter plate, the latch having a hook detachably engageable with said shoulder to lock the attachment in folded position, and having an arm overlying the outer surface of said shorter plate, the arm having a downwardly projecting stud and the plate having a recess frictionally receiving said stud for holding the hook in engagement with the shoulder.

5. An attachment for wrist watch bracelets or the like, comprising upper and lower connector plates pivoted together at one end to swing into folded juxtaposed relation, connections on the respective plates remote from the pivoted ends thereof for securing bracelet ends to the attachment so that the bracelet is extended when the plates are unfolded, the upper plate being shorter than the lower plate and having a transverse pivot pin at its forward extremity, the forward end of the lower plate being bent rearwardly over the upper face thereof and having a shoulder projecting downwardly toward said face, and a latch having a sleeve pivoted on said pin, a hook engageable beneath said shoulder and a lever for releasing the hook from said engagement, the lever lying flatwise upon the outer surface of the upper plate when the latch is engaged to hold the plates in folded position, said surface having an aperture and the lever having a downwardly projecting stud frictionally engaging in said aperture to lock the latch in said position.

6. An attachment for wrist watch bracelets or the like, comprising upper and lower connector plates pivoted together at one end to swing into folded juxtaposed relation, connections on the respective plates remote from the pivoted ends thereof for securing bracelet ends to the attachment so that the bracelet is extended when the plates are unfolded, the upper plate being shorter than the lower plate and having a transverse pivot pin at its forward extremity, the forward end of the lower plate being bent rearwardly over the upper face thereof and having a shoulder projecting downwardly toward said face, and a latch having a sleeve pivoted on said pin, a hook engageable beneath said shoulder and a lever for releasing the hook from said engagement, the lever lying flatwise upon the outer

surface of the upper plate when the latch is engaged to hold the plates in folded position, said surface having an aperture and the lever having a downwardly projecting stud frictionally engaging in said aperture to lock the latch in said position, and means for limiting the rotation of said sleeve.

7. An attachment for wrist watch bracelets or the like, comprising upper and lower connector plates pivoted together at one end to swing into folded juxtaposed relation, the lower plate being longer than the upper plate and having its forward end bent rearwardly over its upper face to provide a loop for connecting a bracelet end thereto, the extremity of said end projecting downwardly toward said face and constituting a shoulder terminating short of said face, the upper plate having an upwardly offset ledge at its forward end and terminating in a tongue rolled downwardly of the ledge, a pivot pin embraced by said tongue, a latch member having sleeves pivoted on the ends of said pin and a hook portion engageable beneath said shoulder, means for releasably holding the hook in engagement with said shoulder to lock the plates in closed position, and a connection on the upper plate disposed rearwardly of the offset ledge for attaching a bracelet end thereto.

8. An attachment for wrist watch bracelets or the like, comprising upper and lower connector plates pivoted together at one end to swing into folded juxtaposed relation, the lower plate being longer than the upper plate and having its forward end bent rearwardly over its upper face to provide a loop for connecting a bracelet end thereto, the extremity of said end projecting downwardly toward said face and constituting a shoulder terminating short of said face, the upper plate having an upwardly offset ledge at its forward end and terminating in a tongue rolled downwardly of the ledge, a pivot pin embraced by said tongue, a latch member having sleeves pivoted on said pin at the opposite ends of said tongue and having a hook engageable beneath said shoulder and a lever overlying said ledge, the ledge having an aperture and the lever having a downwardly projecting stud frictionally engaging in said aperture when the hook is engaged, thereby releasably to lock the plates in closed position, and a tube secured to the upper plate rearwardly of the offset ledge for attaching a bracelet end thereto.

9. An attachment for wrist watch bracelets or the like, comprising upper and lower connector plates pivoted together at one end to swing into folded juxtaposed relation, the lower plate being longer than the upper plate and having its forward end bent rearwardly over its upper face to provide a loop for connecting a bracelet end thereto, the extremity of said end projecting downwardly

toward said face and constituting a shoulder terminating short of said face, the upper plate having an upwardly offset ledge at its forward end and terminating in a tongue 5 rolled downwardly of the ledge, a pivot pin embraced by said tongue, a latch member having sleeves pivoted on said pin at the opposite ends of said tongue and having a hook engageable beneath said shoulder and a lever 10 overlying said ledge, the ledge having an aperture and the lever having a downwardly projecting stud frictionally engaging in said aperture when the hook is engaged, thereby releasably to lock the plates in closed position, said sleeves having peripheral slots and the ledge having downwardly bent side tabs provided with struck out tongues received in the respective slots for limiting the rotation of the sleeves, and a tube secured to the upper 15 plate rearwardly of the offset ledge for attaching a bracelet end thereto.

Signed by me at Providence, Rhode Island,
this 18th day of December, 1929.

CHARLES A. DOMLER.
